CARRYING CASE FOR TENNIS EQUIPMENT OR THE LIKE

Kenneth D. Taylor, Bethany, Okla., assignor to Industrial Plastics Company, Oklahoma City, Okla., a corporation of Oklahoma

Filed July 27, 1964, Ser. No. 31,033

Term of patent 14 years

(Cl. D87—5)

FIG. 1

FIG. 1 is a top front perspective view of a carrying case for tennis equipment or the like, showing my new design;

FIG. 2 is a bottom rear perspective view thereof; and FIG. 3 is an end elevational view thereof.

I claim:

The ornamental design for a carrying case for tennis equipment or the like, as shown.
